UNITED STATES PATENT OFFICE.

WILLIAM A. BAUM, OF NEW YORK, N. Y.

DESIGN FOR A PORTABLE MANOMETER CONTAINER.

Application filed June 16, 1922. Serial No. 2,704. Term of patent 3½ years.

To all whom it may concern:

Be it known that I, WILLIAM A. BAUM, a citizen of the United States of America, and a resident of the city of New York, in the county of Queens and State of New York, have invented a new, original, and ornamental Design for Portable Manometer Containers, of which the following is a specification, reference being had to the accompanying drawing, forming part thereof.

The figure is a perspective view of a portable manometer container, showing my new design.

I claim:

The ornamental design for a portable manometer container, as shown.

WILLIAM A. BAUM.
